UNITED STATES PATENT OFFICE.

CARL P. NACHOD, OF PHILADELPHIA, PENNSYLVANIA.

TROLLEY-SWITCH.

No. 922,024.

Specification of Letters Patent.

Patented May 18, 1909.

Application filed October 27, 1908. Serial No. 459,735.

To all whom it may concern:

Be it known that I, CARL P. NACHOD, a citizen of the United States, residing in the city of Philadelphia, county of Philadelphia, and State of Pennsylvania, have invented a new and useful Trolley-Switch, of which the following is a specification.

My invention relates to a switch or contact device whereby, in an electrical or other railway system, a traveling contact closes a circuit or makes connection between a pair or plurality of contacts.

For brevity, I term my invention a "trolley switch", for its most frequent use is in connection with a trolley wire or contact conductor of an electric railway system, the trolley wheel or contact device bridging or making contact between two or more contacts, one of said contacts being generally connected to the trolley wire or contact conductor. Such a trolley switch is used, for example, in a signaling system, the switch being located at any desired point and as the trolley wheel or traveling contact passes the same a signal circuit is closed or a conductor of the signaling system is brought into communication with the feeder, or trolley wire or other contact conductor.

It is the object of my invention to provide such a trolley switch which may be supported by or in operative relation with a trolley wire or other contact conductor, the contacts being strips of metal extending in the direction of the trolley wire or contact conductor and so mounted as to be resilient or yielding, and so mounted that the trolley wheel or contact device in its travel leaves the trolley wire or other contact conductor, and, without shock or jar, rides upon the longitudinally disposed contacts, bridging them, and finally riding off the contacts without jar or shock on to the trolley wire or contact conductor.

My invention resides in other features hereinafter pointed out and claimed.

For an illustration of one of the forms my invention may take, reference is to be had to the accompanying drawing, in which:

Figure 1 is a top plan view of the trolley switch. Fig. 2 is a side elevational view, a part of the hanger or support being shown in section. Fig. 3 is an end elevation. Fig. 4 is a vertical transverse sectional view taken on the line X—X of Fig. 1. Fig. 5 is a transverse sectional view, partly in eleva-

tion, taken on the line Y—Y, Fig. 1. Fig. 6 is a transverse sectional view taken on the line Z—Z, Fig. 1, some parts being omitted.

In the drawing, A is a hanger member of a double curve pull-off or hanger similar to the type commonly used for suspending a trolley wire or other contact conductor over a trackway of an electric railway. The hanger member A terminates in ears *a* through which extend the bolts *b* which also pass through the eyes *c* of the bolts or pins *d* which extend into the masses of insulating material *e*. Each insulator *e* carries a second eye bolt or pin *d* in the eye *c* of which is secured the span or supporting wire extending across the trackway and supported by suitable poles or other means. Thus the hanger is supported by but insulated from a span or other wire extending across the trackway at substantially right angles to the trackway. The hanger member A has a central hub or boss *f* through which passes a bolt *g* having at its lower end a squared head *h*, of a thickness substantially equal to the diameter of the bolt, and perforated in a direction transverse to the trackway to permit the passage of a bolt *i*. The bolt *i* extends also through the vertical flanges or webs of the longitudinally extending light angle irons *j* and *j'*, forming a frame, the head *h* of the bolt *g* being clamped between them, and the bolt *i* clamping the blocks *k*, *k* of wood or other suitable insulating material, to the angle irons.

The angle irons *j*, *j'* extend throughout the entire, or substantially entire length of the switch, about half of the length being shown in Figs. 1 and 2, the switch being shown broken off a short distance to the right of the line Z—Z, or center of the switch, the right hand portion not shown being similar to the left hand portion about to be described, except that the connectors *p* and *z* may be omitted.

At the left end, as shown in Figs. 1, 2 and 4, blocks *l*, *l*, of wood or other suitable insulating material, are secured by bolts *m*, *m*, to the angle irons *j*, *j'* and a horizontal bolt *n* passes through the blocks *l*, *l* through both angle irons, and through the block *o* of wood or other insulating material separating the vertical webs or flanges of the angle irons. To the right of the block *o* a short bolt *n'* passes through and clamps the vertical flanges of the angle irons.

Secured to one block l , by the bolts p and p' , is a longitudinally extending metal contact strip q . And by bolts r , r' a similar longitudinally extending metal contact strip s is secured to the other block l . At a short distance from the end of the switch, these contact strips q , s , which have their contact faces inclined to each other and convergent toward the top, are bent downwardly or inclined as at t , Fig. 2, and then extend horizontally again until near the other end of the switch where they bend upwardly to be secured to blocks corresponding to l , l . The contacts q , s are resilient and yield under the pressure of the trolley wheel or traveling contact shown at u in dotted lines, Fig. 3. At the middle of the switch the contacts q , s normally stand off the blocks l , l a short distance and excessive yielding is prevented by their coming in contact with such blocks, as will be observed in Fig. 6.

T represents the trolley wire or contact conductor with which, at points other than at the trolley switch, the traveling contact or trolley wheel u engages in a well known manner. Approximate one end of the trolley switch the trolley wire is engaged by the clamp or trolley ear v , held by the bolt w between whose head and the top flanges of the angle irons j , j' intervene washers w' ; and between these washers is clamped a connecting wire w whose other end connects with the bolt r and thus makes electrical communication between the trolley wire T and the longitudinally extending contact s . To the right, as viewed in Figs. 1 and 2, of the trolley ear v the wire T is bent upwardly at y , the bent portion being covered with suitable insulating tape or other material, as desired. Then, the wire T extends horizontally again and is supported by a metal stirrup or strap z whose upper ends are secured to the lower end of a threaded pin or bolt z' passing downwardly between the angle irons j , j' , the pin or bolt z' being drawn upwardly and locked by the nuts z'' , a washer j'' intervening between them and the top flanges of the angle irons j , j' , being preferably secured thereto by rivets or the like. Indeed, the switch may be applied to or associated with the trolley wire T without cutting that wire. The stirrups or straps z are placed around the wire T and then the bolt z' drawn up by the nuts thus lifting the wire T to the position shown intermediate the ends of the trolley switch, such fastening serving both to draw the trolley wire T out of the path of the traveling contact u and affording a steady means or support for the switch with regard to the wire T . Instead of the straps z the trolley wire T may be held by a bolt underneath it, passing through the vertical flanges of the angle irons j , j' . The principal support for the switch is by means of the hanger mem-

ber A , previously described. The other longitudinally extending contact q is electrically connected with the bolt p which supports it and with the bolt p communicates a wire p'' , which leads to the signaling circuit or apparatus. 70

Assuming the trolley wheel or traveling contact u to be passing from right to left, as viewed in Figs. 1 and 2, it travels along in contact with the under side of the trolley 75 wire T until it comes under the portions of the contacts q , s bolted to the blocks l , l . As it advances to the bent-down portions t of these contact strips the rims or edges of the trolley wheel u engage the flat sides of 80 the contact strips q , s and the trolley rides down as it advances, leaving the wire T and maintaining contact with its edges as it travels along the strips q , s . During such travel the strips q , s yield or are resilient, 85 current passing from the contact strip s through the trolley wheel u to the contact q , then out through the signal conductor p'' for the purposes intended. If the vehicle carrying the trolley wheel u is at 90 this time consuming power, current will pass directly from the contact s to the trolley wheel u and thence down to the motors or other translating devices. The oppositely inclined contact faces of the strips 95 q , s center the trolley wheel and prevent its running off. Thus, it is seen that the trolley wheel, even when traveling at high speed, comes under the switch and without shock or jar leaves the trolley wire T and thence 100 travels along the depressed or lowermost portions of the contacts q , s and in leaving the switch, rides up again upon these strips and, finally, makes contact again with the trolley wire T , and passes onward. 105

The inclining of the contact surfaces of the strips q , s has an advantage also from the fact that trolley wheels usually vary in thickness and diameter, according to the service required. Thicker wheels will 110 merely ride on the strips at a lower level. Thus local and interurban cars having different wheels will all operate the switch.

The relatively great distance between the supports for the strips q , s permits the use 115 of relatively thick material for the strips, insuring long life before wearing out, and yet providing sufficient resiliency or flexibility.

From the foregoing description it is apparent that I have provided a switch in which the traveling contact leaves the contact conductor and travels along the longitudinally extending resilient or yielding contact strips, the transition being without shock or jar; 120 and that the switch is applied without cutting or otherwise disturbing the trolley wire or contact conductor. The flexibility or yielding of the contact strips insures that the trolley wheel shall not be thrown even 130

when traveling at high speed. Furthermore, this trolley switch has no moving parts and does not project below the trolley wire. Furthermore, it is immaterial whether the vehicle carrying the trolley wheel is consuming power or not, inasmuch as the contact between the longitudinally extending strips is made irrespective of whether or not the vehicle is consuming power through the trolley wheel.

10. What I claim is:

1. In a device of the character described, the combination with a longitudinally extending frame, of longitudinally extending contact strips supported approximate their ends by said frame and yielding laterally between their supports and insulated from each other, and means for supporting said frame.

20. 2. In a device of the character described, the combination with a longitudinally extending frame, of means for supporting the same in proximity to a contact conductor, and longitudinally extending contact strips 25 themselves resilient and laterally yielding supported by said frame and insulated from each other.

3. In a device of the character described, the combination with a frame comprising 30 longitudinally extending beam members secured together, of longitudinally extending contact strips, and supports secured to said frame for supporting said contact strips, said strips being yielding between supports.

35. 4. In a device of the character described, the combination with a longitudinally extending metal frame, of yielding longitudinally extending contact strips supported by said frame approximate the ends of said 40 frame and insulated from each other.

5. In a device of the character described, the combination with a longitudinally extending frame, of longitudinally extending contact strips supported at the ends of said 45 frame, said contact strips being depressed between supports.

6. In a device of the character described, the combination with a longitudinally extending frame, of longitudinally extending 50 laterally yielding contact strips supported at the ends of said frame, the contact faces of said strips being inclined with respect to each other.

7. In a device of the character described, the combination with a longitudinally extending frame, of longitudinally extending contact strips supported at the ends of said 55 frame, the contact faces of said strips being inclined with respect to each other, and said strips being depressed between supports.

8. In a device of the character described, the combination with a longitudinally extending frame, of longitudinally extending contact strips supported at the ends of said 60 frame, said contact strips being yielding be-

tween supports, and means intermediate said supports for limiting the deflection of said contact strips.

9. In a device of the character described, the combination with a longitudinally extending frame, of a contact conductor, means upon said frame approximate an end thereof for receiving said contact conductor, means upon said frame for holding said contact conductor in elevated position, and laterally yielding longitudinally extending contact strips supported approximate the ends of said frame.

10. In a device of the character described, the combination with a supporting frame, of 80 a contact conductor, means upon said frame for holding said contact conductor out of the path of a traveling contact, and laterally yielding longitudinally extending contact strips supported approximate the ends of 85 said frame.

11. In a device of the character described, the combination with a contact conductor, of 90 longitudinally extending laterally yielding contact strips disposed in proximity thereto, said contact strips being depressed and said contact conductor elevated, whereby a traveling contact leaves said contact conductor and engages said contact strips.

12. In a device of the character described, 95 the combination with a longitudinally extending frame, of an associated contact conductor, longitudinally extending laterally yielding contact strips, supports therefor at the ends of said frame, said contact strips 100 being depressed between said supports and said contact conductor elevated between said supports.

13. In a device of the character described, the combination with a longitudinally extending frame, of a support therefor intermediate its ends, longitudinally extending laterally yielding contact strips, supports therefor at the ends of said frame, an associated contact conductor, and means on said 110 frame for drawing up said contact conductor out of the path of a traveling contact.

14. The combination with a contact conductor, of a longitudinally extending frame associated therewith, longitudinally extending laterally yielding contacts supported by 115 and approximate the ends of said frame, and means on said frame for engaging said contact conductor and associating said contact strips in operative relation without cutting 120 said contact conductor.

15. The combination with a contact conductor, of a longitudinally extending frame disposed in proximity thereto, longitudinally extending laterally yielding contact strips 125 supported by and approximate the ends of said frame, an electrical connection between said contact conductor and a contact strip, and an external connection with another of 130 said contact strips.

16. In a device of the character described, the combination with a longitudinally extending frame, of longitudinally extending laterally yielding contact strips supported thereby, said contact strips depressed between the ends of said frame and elevated at the ends of said frame, and inclined portions joining said elevated and depressed portions.
17. In a device of the character described, the combination with a longitudinally extending frame, of longitudinally extending laterally yielding contact strips supported thereby, said contact strips being depressed between the ends of said frame and elevated at the ends of said frame, inclined portions joining said elevated and depressed portions, and an associated contact conductor, said contact conductor being elevated intermediate said inclined portions of said contact strips.
18. In a device of the character described, the combination with longitudinally extending support, of blocks of insulating material secured thereto at the ends thereof, and longitudinally extending contact strips secured to said blocks and yielding between supports.
19. In a device of the character described, the combination with longitudinally extending angle irons secured together and having
- their flanges disposed vertically and horizontally, of means disposed between said angle irons and extending upwardly to form a support, blocks of insulating material secured to the ends of said angle irons, and longitudinally extending contact strips secured to said blocks.
20. In a device of the character described, the combination with a longitudinally extending frame, of longitudinally extending laterally yielding contact strips supported at the ends of said frame, the contact faces of said strips being convergent toward the top.
21. In a device of the character described, the combination with a longitudinally extending frame, of longitudinally extending contact strips convergent toward the top secured thereto approximate the ends thereof and yielding laterally between supports, said contact strips being depressed between the ends of said frame and elevated approximate the ends of said frame, and inclined portions joining said elevated and depressed portions.

In testimony whereof I have hereunto affixed my signature in the presence of the two subscribing witnesses.

CARL P. NACHOD.
